AIR CUSHION VEHICLE

Geoffrey Voyce, Ottawa, Ontario, Canada, assignor to
MHV Industries Limited, a corporation of Canada

Filed Sept. 24, 1969, Ser. No. 19,281

Claims priority, application Canada May 23, 1969

Term of patent 14 years

Int. Cl. D12—13

U.S. Cl. D71—1

FIG. 1

Des. 219,077

PAGE 2

Des. 219,077

PAGE 3

FIG 4

FIG 5

FIG. 1 is a perspective view of the air cushion vehicle looking from the side and slightly above the vehicle;

FIG. 2 is a side elevation view;

FIG. 3 is a top plan view;

FIG. 4 is a front elevation view; and

FIG. 5 is a rear elevation view.

I claim:

The ornamental design for an air cushion vehicle, substantially as shown.
